UNITED STATES PATENT OFFICE.

ARTHUR J. CLINTON, OF PAOLA, KANSAS, ASSIGNOR OF ONE-HALF TO CHARLES W. NEISREVENDER, OF PAOLA, KANSAS.

SHADE HANGING AND OPERATING MEANS.

Application filed February 13, 1925. Serial No. 8,995.

To all whom it may concern:

Be it known that I, ARTHUR J. CLINTON, a citizen of the United States, residing at Paola, in the county of Miami and State of Kansas, have invented certain new and useful Improvements in Shade Hanging and Operating Means, of which the following is a specification.

This invention relates to improved means 10 for hanging and operating shades having spring rollers, and the primary object of this invention is to provide means of this character which will enable one to readily obtain a desired amount of light and ventilation through the upper part of a window 15 as well as the lower part thereof.

I accomplish the above object by the provision of improved means for hanging a window shade whereby its roller may be 20 adjusted vertically of the window to assume any desired position between the upper part of the window opening and the central part thereof when the window sashes are closed, and whereby the range of adjustment may 25 be increased to still further lower the shade and its roller when the upper sash is lowered or opened.

Another object of the invention is to provide means for automatically unrolling the 30 shade as it is adjusted upwardly from its normal position substantially mid-way between the top and bottom of the window opening, in which normal position the shade is substantially entirely rolled upon its 35 roller.

Still another object of the invention is to provide improved means for accomplishing the last of the above mentioned objects, which means also provides means for placing 40 the spring of the shade roller under tension when the shade is unrolled by manually pulling the same downwardly in the usual well known manner.

Still another object of the invention is to 45 provide improved means for securing the shade roller in its various vertical adjustments.

With the above general objects in view, and others that will become apparent as the 50 nature of the invention is better understood, the same consists in the novel form, combination and arrangement of parts hereinafter more fully described, shown in the accompanying drawings, and claimed.

In the drawings, wherein like reference

characters indicate corresponding parts throughout the several views,

Figure 1 is a front elevational view, partly broken away, showing a window provided with the shade supported or hung in accordance with the present invention, 60

Figure 2 is a substantially central vertical sectional view of the device shown in Figure 1,

Figure 3 is a fragmentary side elevational 65 view of the device shown in Figure 1, with the shade roller pulley in section,

Figure 4 is an enlarged fragmentary sectional view illustrating one of the mounting brackets for the shade roller, 70

Figure 5 is a fragmentary rear elevational view showing the shade roller supporting bar together with adjacent portions of the guide rod thereof and the means for maintaining the supporting bar in adjusted positions on said guide rod, 75

Figure 6 is a fragmentary sectional view taken substantially upon line 6—6 of Figure 5,

Figure 7 is a fragmentary sectional view 80 taken substantially upon line 7—7 of Figure 3,

Figure 8 is a sectional view taken on the line 8—8 of Figure 1.

Referring more in detail to the drawing, 85 5 indicates a window frame in which is mounted the usual vertically sliding upper and lower sashes 6 and 7 respectively. In accordance with the present invention a pair of vertical guide rods 8 are attached 90 to the upper rail or the upper corners of the frame of the upper sash 6, these guide rods being of angular form so as to provide inwardly extending upper end portions and depending vertical portions, which vertical portions extend in a plane inwardly of the plane of the lower sash 7. In order to steady the guide bars 8 and maintain them 95 in their proper vertical position while at the same time permitting the same to raise and lower with the upper sash 6 to which they are attached, the vertical portions of said guide rods slidably extend through guides or eyelets 9 which are fastened to the upper corners of the lower sash 7. The vertical portions of the guide rods 8 are sufficiently long to stay within the guides 9 when the sashes 6 and 7 are entirely closed. 100

The invention further embodies a horizontal shade roller supporting bar 10, the 110

ends of which extend outwardly across the guide bars 8 and are provided with U-shape brackets 10' whose leg portions project across the upper and lower edges of the bar 10 and outwardly of the latter towards the sashes where such legs of the bracket are provided with vertically aligned openings through which the guide bars 8 slidably extend. The supporting bar 10 is thus associated with the guide bars 8 for vertical adjustment relative to the latter, and suitable brackets 11 and 12 are secured upon the ends of the bar 10 for supporting a conventional form of spring roller 13 upon which is wound a shade 14. The roller 13 is conventional in every respect except that the spring operated shaft 15 thereof at one end is provided with an extension upon which is secured a pulley or drum 16 about which passes a flexible member or cord 17 whose upper end is attached as at 18 to the adjacent side of the frame 5 near the top of the latter, the lower end of the cord 17 being attached releasably as at 19 to a suitable retaining member secured to the frame 5 below the roller or pulley 16. The cord 17 is placed under sufficient tension to frictionally engage the pulley 15 whereby the spring shaft 15 of the roller 13 is held against rotation when the shade is grasped and pulled downwardly for unrolling the same, whereby the spring of the roller 13 is placed under tension in the usual manner so as to furnish energy for rewinding the shade upon the roller 13 in the usual way.

As shown more clearly in Figures 4 and 8 the bracket 12 has a circular opening for reception of the flattened portion 20 of the spring shaft 15 whereby said shaft is permitted to rotate in this bracket under certain conditions, the bracket being further provided with a restricted entrance slot as at 21 communicating with the circular opening for permitting engagement of the shaft 15 with the bracket and removal of the same therefrom when the flattened portion is disposed horizontally. Thus accidental displacement of the spring shaft of the shade roller from the bracket 12 is prevented although its intentional removal is allowed, the slot 21 being substantially of the same width as the narrow dimension of the flattened portion 20 of the shaft 15. By reason of the construction of the bracket 12 permitting the rotation of shaft 15, and the engagement of the cord 17 with the pulley 16, raising and lowering of the supporting bar 10 will respectively effect unrolling of the shade from the roller 13 and rolling of the same thereon. In other words, when the supporting bar 10 is moved upwardly the entire shade roller is rotated for unwinding the shade without affecting a change in the tension of the spring of the shade roller 13 while lowering of the bar 10 to its normal

position as shown in Figure 1 will effect rerolling of the shade on the roller 13 also without effecting the tension of the spring of the shade roller. This action is automatic by reason of the frictional engagement of the cord 17 with the pulley 16 and the ability of the shaft 15 to rotate in bracket 12.

Means is provided for maintaining the bar 10 in any of its vertically adjusted positions relative to the guide bars 8, and this means preferably embodies releasable holding devices associated with each end of the bar 10 and cooperating with the adjacent guide bar 8. As each device is similarly constructed description of one will suffice, particular attention being directed to Figures 5 and 6 in connection with this construction. Each holding device comprises a bracket the intermediate portion of which embraces the adjacent guide rod 8 as at 22, and the end portions of which are directed away from each other in the form of feet 23 which are secured to the bar 10 by means of screws or the like, the bracket 22 being disposed between the horizontal legs of the adjacent U-shaped bracket 10' through which the adjacent rod 8 slidably extends. Attached to the bar 10 inwardly of each rod 8 is a helical tension spring 24 the outer end of which is formed with a loop 25 that embraces the adjacent guide rod 8 and that is provided upon its free outer end with a hook 26 or other suitable means for attaching the same to a lever 27 that is pivoted to the adjacent bracket 22 at its lower end as at 28 for swinging movement in a vertical plane. The loop 25 is movable in a slot 29 provided in the adjacent bracket 22, and the spring 24 normally acts to draw the loop portion 25 tightly against the rod 8 so as to grip the latter and maintain the bar 10 against movement along the guide bar 8. The fastening devices thus constructed, while being of similar construction are of right or left hand types so that separation of the levers 27 thereof or outward swinging of the same is necessary for release of the device whereby the bar 10 may be freely moved relative to both of the guide rods 8. The levers 27 are relatively short and preferably have their upper ends directed away from the sashes so that they may be readily engaged by the finger for their actuation. The holding means or devices are thus normally active and manually released.

With the parts arranged as shown in Figure 1 light will be permitted to pass through substantially all or both of the sashes while unobstructed ventilation will be had at the upper part of the window by reason of the upper sash 6 being partially lowered or opened. Obviously, the same amount of light may be had together with better ventilation from the upper part of the window by releasing the holding de-

5 vices including the levers 27 and lowering the upper sash 6 to the desired extent, the release of the holding devices being necessary in case the upper sash is to be lowered a greater distance than the bar 10 can be lowered by reason of the guides 9. The same amount of ventilation and light may be had at the upper part of the window while the entrance of light through the 10 lower part of the window can be cut off by simply drawing the shade downwardly from its position in Figure 1. On the other hand, the bar 10 may be released and slid upwardly on the guide bar 8 so as to cut 15 off light from any desired part of the upper part of the window when the shade is unrolled to the desired extent so that light or ventilation or both may be obtained only through the lower part of the window. In 20 this way the construction provides for securing any desired possible amount of light or ventilation through either the upper or lower portions of the window, a result which can not be secured when the shades are hung 25 in the usual way by stationary brackets rigidly fastened to the upper part of the window frame.

From the foregoing description it is believed that the construction and operation as 30 well as the advantages of the present invention will be readily understood and appreciated by those skilled in the art.

What I claim as new is:—

35 1. In a device of the character described, a supporting bar, means to hold said supporting bar in a horizontal position adjacent a window for vertical adjustment relative to the latter, means to retain said bar in any desired vertically adjusted posi-

tion, a spring shade roller disposed inwardly 40 of the supporting bar and having a spring actuated shaft provided with a projecting end portion of flat form intermediate its ends, brackets secured on the ends of the supporting bar in which the pintle and 45 spring actuated shaft of the shade roller are removably journaled, one of said brackets having a circular opening in which the flat portion of said shaft is rotatable and provided with a restricted entrance slot for 50 said opening through which the flat portion of said shaft is movable, a pulley on the outer end of said projecting end portion of said shaft, and a flexible member adapted to have its intermediate portion wound about the pulley and its ends attached to the window frame above and below said bar whereby vertical adjustment of the latter will cause turning of the shade roller and whereby said shaft is held from rotation 55 when the shade of the roller is rolled or unrolled and said bar is held in its adjusted position.

2. In a device of the character described, a vertical guide rod, a supporting bar slidably associated with said guide rod, a helical tension spring having one end attached to said supporting bar, a hand lever pivoted to said supporting bar and having the other end of said spring attached thereto, and a 60 loop formed on said other end of the spring inwardly of the lever and embracing and frictionally engaging the guide rod to releasably retain the supporting bar against movement on the guide rod. 75

In testimony whereof I affix my signature.

ARTHUR J. CLINTON.
